UNITED STATES PATENT OFFICE.

FRANKLIN A. WELLER AND ADOLPH F. RIETZEL, OF LYNN, MASSACHUSETTS.

ELECTRIC SWITCH.

SPECIFICATION forming part of Letters Patent No. 398,561, dated February 26, 1889.

Application filed December 26, 1888. Serial No. 294,619. (No model.)

To all whom it may concern:

Be it known that we, FRANKLIN A. WELLER and ADOLPH F. RIETZEL, both of Lynn, in the county of Essex, State of Massachusetts, have 5 invented a certain new and useful Improvement in Electric Switches, of which the following is a description sufficiently full, clear, and exact to enable any person skilled in the art or science to which said invention appertains 10 to make and use the same, reference being had to the accompanying drawings, forming part of this specification, in which—

Figure 1 is a top plan view of our improved switch, the cap being removed; Fig. 2, a vertical transverse section taken on line $x-x$ in Fig. 1; Fig. 3, a like view taken on line $y-y$ in Fig. 1, and Fig. 4 a vertical section taken on line $z-z$ in Fig. 1.

Like letters and figures of reference indicate 20 corresponding parts in the different figures of the drawings.

Our invention relates to that class of switches especially adapted for use with electric-light wires, and known as "double-pole switches;" and it consists in certain novel features, as hereinafter fully set forth and claimed, the object being to produce a simpler, cheaper, and otherwise more effective device than is now in ordinary use.

30 The nature and operation of the improvement will be readily understood by all conversant with such matters from the following explanation:

In the drawings, A represents the switch 35 table or body, and B the cap or ease.

The table consists of the circular wooden plate common in switches of this class, and is chambered at b on its under side, and provided with screw-holes d, by which it may be 40 readily secured in the position desired.

A metallic bed-plate, f, is secured to the face of the table by screws g and extends transversely across the same. A vertically-arranged metallic standard, h, preferably circular in form, is secured centrally to the plate 45 f, and fitted to slide on said standard there is a metallic tube, i. A horizontally-arranged metallic strip, j, is secured centrally to the top of the tube i and projects laterally from each 50 side thereof, the ends of said strip or plate being bent back against the body thereof and

secured thereto by screws k, as best shown in Fig. 1. A metallic plunger, l, (see Fig. 4,) preferably composed of a single plate of phosphor-bronze bent into the shape of the letter "h," 55 when viewed in side elevation, is secured by its upper end in each end of the plate j, being clamped therein by means of the screw k, and thereby rendered vertically adjustable.

Insulating material m, preferably indurated 60 fiber, is interposed between the plungers and plates j. Two phosphor-bronze plates, p q, are secured to the table A by screws r t at each side of and parallel with the bed-plate f, the rear screws, t, being provided with washers v for clamping the conducting-wires N P onto the plates p q, said screws serving as poles or connectors for said wires, which pass upward through openings w in the table. The adjacent free ends of the plates p q are 70 bent vertically upward, (see Fig. 4,) forming sockets 15 for the plungers l.

A horizontally-arranged lever, D, is pivoted on a screw-bolt, 25, disposed in the forward portion of the table A and plate f, said lever 75 being provided with a handle, 35, on its outer end, and having its inner end, 55, bent upward and outward, as shown in Fig. 3.

A flat spring, 45, (see Fig. 3,) is secured by one end in the handle 35, and is provided 80 with a cup-shaped head, which bears against the head of the bolt 25, its purpose being to prevent the lever D from being accidentally moved on said bolt.

A spring, 65, consisting of a finely-tempered 85 piece of wire bent to form a head, 75, which is arranged diagonally to the horizontal plane of the lever D, is secured by a screw, 85, and washer 95 to the end 55 of said lever.

A vertical post, 14, is secured to the bed-plate f in front of the standard h, said post being provided on its upper end with an outwardly-projecting arm, 24, which projects into the path of the head 75 of the spring 65, the course of which is represented by the dotted 90 line 34 in Fig. 1.

Two outwardly-projecting arms, 44 and 54, are secured to the tube i in position to be engaged by the head of the spring 65, as herein-after described, the arm 44 being farther from 100 the bed-plate than the arm 54.

The guide-rod 64 is secured by one end to

the rear of the tube *i*, said rod projecting downward through an opening, 74, in the bed-plate and table. The rod 64 is fitted to work vertically in one end of a forked plate, 84, secured by a set-screw, 94, to the bed-plate *f*, the purpose of said plate 84 being to secure the guide-rod in position, and thereby adjust the plate *j*, in which the plungers are secured, the opening 74 in the table being of sufficient width to allow lateral movement of said guide-rod.

A vertically-arranged spring, 13, is secured to the bed-plate and engages the upper portion of the guide-rod, its purpose being to prevent the tube *i* from being accidentally moved on the standard *h*.

The cap or case *B* is designed to inclose the device upon the table *A*, and is secured thereon by a screw, 23, in the top of the standard *h*, which projects through a slot in the top of said case. The cap is also provided with an opening in its side, through which the lever *D* projects. A washer, 33, disposed on the screw 23, serves as a stop to prevent the tube *i* from being elevated too far.

In Figs. 2, 3, and 4 the tube *i* is represented as elevated on the standard *h* and the plungers *l* disconnected from their sockets 15. When the switch is in this position, if it is desired to close the circuit, the handle 35 of the lever *D* is moved from left to right, causing the diagonally-arranged head 75 of the spring 65 to ride over the arm 24 of the post 14, which forces said spring upward, so that in resuming its normal position after leaving said arm it will forcibly strike the arm 54 on the tube *i* and drive said tube downward on the standard *h*, thereby bringing the plungers *l* into contact with the plates forming their sockets, the parts assuming the position shown in Fig. 1. To break the circuit again, the lever *D* is moved in the opposite direction, the spring-head 75 being in this case forced downward by the post-arm 24 and strikes the arm 44 from below, thus driving the tube *i* upward and disengaging the plungers from their sockets.

It will readily be seen that by adjusting the guide-rod 64 by means of the plate 84, and thus revolving the tube *i* on the standard, the plungers may be arranged to make perfect contact with the plates forming their sockets. Moreover, the plungers being shaped as described and composed of phosphor-bronze, they may be readily bent so that their contact-surface with their socket-plates may be enlarged. By means of the clamping ends of the plate *j* the plungers may also be vertically adjusted, so that they will leave and come in contact with their sockets simultaneously.

Having thus explained our invention, what we claim is—

1. In an electric switch, the lever *D*, piv-

oted on the bolt 25 and provided with the retaining-spring 45, in combination with the spring 65, provided with the diagonally-arranged head 75, substantially as and for the purpose set forth.

2. In an electric switch, the combination of a table provided with a standard, a tube fitted to slide on said standard and bearing sheet-metal plungers, connector-plates on said table forming sockets for said plungers, a pivoted lever provided with a spring having a diagonally-arranged head, a post for distending said spring, and arms on said tube for receiving said spring as it leaves said post, whereby said plungers are actuated, substantially as described.

3. In a switch, the tube *i*, fitted to slide on the standard *h* and provided with the clamping-plate *j*, in combination with the guide-rod 64 and plate 84, whereby said clamping-plate may be adjusted horizontally, substantially as described.

4. In an electric switch, the combination of a table provided with connector-plates bent to form plunger-sockets, a bed-plate provided with a standard, a tube fitted to slide on said standard and provided with sheet-metal plungers adapted to engage said sockets, a lever pivoted to said table, a spring secured to said lever and provided with a cam-shaped head, a post on said bed-plate for engaging said cam-head and distending the spring, and arms on said tube projecting into the path of said spring, whereby the plungers may be forced into contact with or disconnected from their sockets, substantially as described.

5. In an electric switch, the combination of the table *A*, provided with the connector-plates *p q*, bent to form sockets 15, the bed-plate *f*, provided with the standard *h* and post 14, the lever *D*, the spring 65, having the cam-head 75, the tube *i*, provided with the clamping-plate *j*, and arms 44 and 54, projecting into the path of said spring, the plungers *l*, adjustably secured in said clamping-plates, and the guide-rod 64 and plate 84, whereby said plungers may be adjusted horizontally, all being arranged to operate substantially as set forth.

6. In an electric switch, a pivoted lever provided with a spring having a cam-shaped head, in combination with a standard for engaging and distending said spring when the lever is moved, and a tension-spring secured to said lever and bearing upon the pivot thereof, substantially as and for the purpose specified.
